UNITED STATES PATENT OFFICE

2,481,441

FUEL INJECTOR

Ben G. Parsons, Grosse Pointe, Mich., assignor to
 Fuel Charger Corporation, Detroit, Mich., a
 corporation of Michigan

Application May 11, 1945, Serial No. 593,294

3 Claims. (Cl. 103—173)

1

The present invention relates to improvements in fuel injectors and particularly to improvements in multiplunger gasoline injectors for use with internal combustion engines.

One of the primary objects of the invention is to provide improvements in the structure for adjustably controlling the amount of fuel delivered by the plungers in injectors of the type mentioned.

A further object of the invention is to provide a simplified injector construction of the type mentioned which lends itself to accurate, economical mass production.

Other objects of the invention will become apparent from the following specification, the drawings relating thereto, and from the claims hereinafter set forth.

In the drawings in which like numerals are used to designate like parts in the several views throughout:

Figure 1 is a side elevational view of a fuel injector embodying features of the present invention;

Figure 2 is an end elevational view of the structure shown in Figure 1 and taken from the left end thereof;

Figure 3 is a cross-sectional view taken along the line 3—3 of Figure 2;

Figure 4 is an end elevational view of the structure shown in Figure 3 taken from the right end thereof, with parts broken away and illustrating such parts in cross section taken substantially along the line 4—4 of Figure 3;

Figure 5 is a separated view, showing certain of the parts in cross section and certain in elevation of the parts making up the assembly and showing such parts in their relationship for assembly;

Figure 6 is a view similar to Figure 5 and illustrating the remainder of the parts in their relationship for assembly to the right of Figure 5;

Figure 7 is a cross-sectional view of the ball cup for connecting the plunger to the swash plate;

Figure 8 is an elevational view of the ball head screw;

Figure 9 is a cross-sectional view of the ball ring;

Figure 10 is a cross-sectional view of one of the plungers;

Figures 7, 8, 9, and 10 are illustrated in the drawing in their relative positions for assembly; and

Figure 11 is a fragmentary, elevational view of a portion of the wobble plate.

2

Referring to the drawings, the fuel injector of the present invention is generally indicated at 1 and comprises a pump or injector body 2 having a plurality of circumferentially spaced, longitudinally extending plunger barrels or bores 3. There are nine of such plunger barrels 3 in the embodiment illustrated, the particular injector here illustrated being designed for distributing fuel to nine cylinders. An inlet port 4 is formed through the wall of the body 2, for each of the bores 3, and communicating therewith. An annular groove 5 is formed in the periphery of the body 2 around the inlet ports 4 so that all of such ports are in communication. An annular tube fitting 6 embraces the body 2 surrounding the groove 5 and has an inlet tubular projection 7 and a return tubular projection 8 formed thereon. The projection 7 is connected to a suitably flexible conduit leading to a source of supply and the tube 8 is connected to a suitable conduit returned to the source. The fitting 6 is mounted on the body 2 by means of a seal ring nut 9 which is threaded to the body 2. Seal rings 10 are disposed between the opposite sides of the fitting 6 and a shoulder on the body 2 and the adjacent face of the nut 9, to provide a sealed connection for the ring 6 with the body 2.

An axially aligned outlet passage 11 is formed in the body 2 for each of the bores 3. One end of the passage 11 communicates with the inner end of the bore 3 and the opposite end is formed with a valve seat 12. Another bore 13 is formed in the body 2 adjacent each of the valve seats 12. Communication between bore 3 and the chamber formed by bore 13 is controlled by means of a valve 14 having a valve seating portion 15 which is adapted to be seated on valve seat 12. That portion of the valve 14 which is received within the passage 11 is triangular in cross section and has peripheral lands which slidably engage the wall of passage 11 with the intermediate flat portions providing passageways for the passage of fuel from bore 3 into chamber 13 when the valve is open. The valve 14 is normally urged toward its seat by means of a compression spring 16, one end of which bears against the adjacent end of valve 14 and the opposite end of which bears against a retaining screw plug 17. The retaining screw 17 is threadably received within the body 2 and has a washer 18 disposed therebetween.

Each of the chambers 13 communicates with a longitudinally extending discharge passageway 19, formed in the body 2, through an intercon-

necting passageway 28. The passageways 18 are formed as bores through one end of the body 2 and are plugged by screws 21.

Each passageway 18 communicates with another passageway 22 formed in an annular flange 23 of the body 2 with an axial opening 24 formed therein. The injector 1 is suitably mounted on the engine by means of mounting bolts 25 which are passed through the openings 24. A drive shaft housing 26 has a radially extending, annular flange 27 which is mounted to the adjacent face of the flange 23 and separated therefrom by a gasket 28. The flange 27 has openings 29 formed therein corresponding to openings 24, and the mounting bolts 25 extend through such openings 29. For the purpose of mounting the injector 1 to the engine, after the injector is assembled, the assembled parts, including the housing 26, are mounted to the body 2 by means of a plurality of equally spaced screws 30 which are passed through aligned openings 31 formed in flanges 27 and 23. A distributor ring or tube ring (not shown) is mounted to the flange 27 by bolts 25. Such ring may be of the type disclosed in copending application of Ben G. Parsons, Serial No. 568,177 filed December 7, 1944, now Patent 2,405,163 granted Aug. 6, 1946. The mounting bolts 25 pass through the openings 24 and 29 and corresponding openings in the distributor ring. Such bolts 25 have reduced portions 32 which form with the adjacent surfaces of the openings an annular chamber into which the corresponding passageways 22 open and communicate. Tubes mounted on the distributor ring communicate with their corresponding chambers and lead to their particular injector nozzles, which in turn are associated with their particular cylinders.

A plunger 33 is reciprocably and rotatably disposed in each of the bores 3. The inner end of each plunger 33 has a hollow axial recess 34 communicating through the open inner end thereof with the bore 3. A helical groove 35 is formed in the periphery of the plunger 33 adjacent the inner end thereof and communicates with the hollow interior 34 through a plurality of openings 36 formed in the wall thereof. The opposite end of each plunger 33 has another hollow bore 37 formed therein which is tapped to threadably receive an adjusting ball screw 38. The inner end of the ball screw 38 is formed with resilient fingers indicated at 39 so it is of the locking type. The opposite end of the screw 38 has a ball head 40 formed thereon.

The plunger assemblies, including the plungers 33 and the screws 38 are all connected to a swash plate 41. Such swash plate 41 has an annular groove 42 formed therein which opens through the periphery thereof. One of the walls forming the groove 42, indicated at 43, is formed with a plurality of equally spaced slots or grooves 44 through the periphery thereof. There is one of such slots 44 for each of the plungers and the throat of the screw 38 is received within the groove. The width of the groove is slightly greater than the diameter of the adjacent throat portion of the screw 38 so that slight circumferential play is permitted between the swash plate 41 and the plungers. The ball heads 40 are received within the groove 42 and are slidably connected to the opposite faces of groove 42 by means of a ball cup 45 and a ball ring 46. The ball cup 45 is disposed on one side of the ball head 40 and the cup 46 on the opposite side. It will be appreciated that the cup 45 and ring 46

slidably engage the opposite faces of the groove 42 so that sliding movement, radially, is permitted between the ball heads 40 and the swash plate 41 as the swash plate assumes its different angular positions.

The swash plate 41 is mounted on an eccentric drive shaft 47. The drive shaft 47 has axially aligned bearing portions 48 and 49 with an intermediate eccentric portion 50, which is disposed at the desired angle with respect to the axis in order to give the desired stroke to the plungers.

The swash plate 41 has a bearing flange 51 which receives therein the outer race of a ball bearing assembly 52. The inner race of the ball bearing assembly 52 is mounted on the eccentric 50 of shaft 47.

Thus, upon rotation of shaft 47, which rotates relative to the swash plate 41, the swash plate is caused to assume its different angular positions to effect reciprocation of the plungers.

In order to rotatably mount the shaft 47, and for other purposes to be hereinafter described, the body 2 is formed with a central axial opening 53 therethrough. A capacity control shaft 54 is rotatably received within the opening 53 and has an enlarged hollow end 55 which mounts therein the cage of a needle bearing assembly 56. The needle bearing assembly 56 rotatably receives therein bearing portion 49 of shaft 47 for rotatably mounting that end of the shaft. The opposite portion 48 of the shaft 47 is mounted to the inner race of the ball bearing assembly 52 which is mounted within an opening 58 formed in the drive shaft housing 26. The outer end of shaft 47 projects beyond the housing 26 and is suitably formed for driving connection to a suitable drive means.

In order to control the capacity of the injector, that is, to adjustably control the amount of fuel delivered upon reciprocation of plungers 33, means are provided for simultaneously rotating all of the plungers 33 about their own respective axes. It will be appreciated, as shown in Figure 3, that at the beginning of the delivery stroke of each plunger, the inner end of such plunger overlaps its inlet port 4. The amount of fuel delivered by the plungers depends upon the points at which the groove 35 overlaps or communicates with the port 4 for communicating the inlet with the bore 3. It will be understood that the stroke of the pistons is constant; but the effective stroke of the pistons, in relation to the time this communication is established between the bore 3 and the inlet port 4, varies according to the rotative position of the groove 35 with respect to the port 4.

In order to accomplish this adjustment, each of the plungers 33 is formed with longitudinally extending gear teeth 60 in the outer peripheral surface thereof which are adapted to mesh with the gear teeth 61 formed on the annular radial flange of the capacity control shaft 54. By rotating shaft 54 the gear teeth 61 on flange meshing with the gear teeth 60 will cause the plungers 33 to rotate about their axes. The shaft 54 has an axial portion 62 of a capacity control lever 63 splined thereto. The portion 62 of the control lever is rotatably received within an axial bore 64 formed in body 2 through one end and communicating with the opening 53. The lever 63 may be fixed to the shaft 54 by means of a screw 65. In order to limit the rotation of shaft 54 it is formed with radially extending projections 66 which are received within diametrically opposed slots 67 formed in the body 2 between

openings 64 and 53. The slots 67 are of predetermined width to give the desired limited movement.

In the operation of the device above described, with fuel constantly supplied to the inlet ports 4, rotation of shaft 47 effects reciprocation of plungers 33. Movement of the plungers 33 toward the left, viewing Figure 3, effects an intake of fuel to bores 3 through openings 36. Movement of the plungers 33 toward the right, viewing Figure 3, effects delivery of the fuel. During that portion of the delivery stroke in which the groove 35 communicates with port 4, the fuel within bore 3 is returned through the inlet ports, or spilled back through such ports, and as the delivery stroke of the plungers continues, a point is reached where communication between bores 3 and ports 4 is cut off confining the fuel within the bores 3. Further movement of the plungers in their delivery strokes builds up the fuel pressure to delivery pressure at which time the pressure responsive valve 14 is unseated communicating the bores 3 with their respective chambers 13. The fuel is then delivered from chambers 13 to the respective cylinders through passageways 20, 19, 22 and through the distributor ring.

What is claimed is:

1. In a multicylinder liquid pump, a pump body having a plurality of circumferentially spaced, longitudinally extending plunger barrels, an inlet port communicating with each barrel through the side thereof, a delivery port communicating with each barrel through the inner end thereof, a pressure responsive valve in each delivery port, a delivery plunger disposed within each barrel having a hollow delivery chamber in the end facing said delivery port and said end terminating in a plane normal to the longitudinal axis of said plunger, means forming a helical recess partly around the periphery of each plunger and spaced inwardly from said end, an opening through the base of each recess communicating with said chamber, said plungers being disposed in said barrels so that the inner ends thereof overlap said inlet ports, and means connected to said plungers to effect reciprocation thereof, the construction and arrangement of said last-named means, said plungers and said openings being such that, upon reciprocation of said plungers, said inlet ports communicate with said chambers through said openings only.

2. In a multicylinder liquid pump, a pump body having a plurality of circumferentially spaced, longitudinally extending plunger barrels, an inlet port communicating with each barrel through the side thereof, means forming an annular groove in said pump body communicating with all of said inlet ports, an annular member having an inlet opening mounted on said pump body in surrounding relation to said annular groove and forming therewith an inlet passageway, a delivery port communicating with each barrel through the inner end thereof, a pressure responsive valve in each delivery port, a delivery

plunger disposed within each barrel having a hollow delivery chamber in the end facing said delivery port and said end terminating in a plane normal to the longitudinal axis of said plunger, means forming a helical recess partly around the periphery of each plunger and spaced inwardly from said end, an opening through the base of each recess communicating with said chamber, said plungers being disposed in said barrels so that the inner ends thereof overlap said inlet ports, and means connected to said plungers to effect reciprocation thereof, the construction and arrangement of said last-named means, said plungers and said openings being such that, upon reciprocation of said plungers, said inlet ports communicate with said chambers through said openings only.

3. In a multicylinder liquid pump, a pump body, means forming a longitudinal central opening through said pump body, means forming a plurality of circumferentially spaced, longitudinally extending plunger barrels in said pump body surrounding said central opening, an inlet port and a delivery port communicating with each barrel, a pressure responsive valve in each delivery port, a delivery plunger disposed within each barrel with one end of each plunger projecting therebeyond, means formed adjacent the inner end of each plunger to control the amount of liquid delivered according to the relative rotative position of each plunger around its axis, the projecting end of each plunger having gear teeth thereon, a shaft rotatably mounted within said central opening, a gear mounted on said shaft for rotation therewith meshing with the teeth on all of said plungers, means to rotate said shaft, a drive shaft having its axis disposed on the axis of said central opening, a swash plate, means mounting said swash plate on said drive shaft for relative rotation with respect thereto, means connecting said plungers to said swash plate to effect reciprocation thereof upon rotation of said drive shaft, a housing mounted on said pump body enclosing said drive shaft and said swash plate, anti-friction bearing means mounted on said housing and supporting said shaft adjacent the outer end thereof, and anti-friction bearing means mounted within said central opening and supporting the inner end of said drive shaft.

BEN G. PARSONS.
